Inventor,

William J. Healy

UNITED STATES PATENT OFFICE.

WILLIAM J. HEALY, OF SUSQUEHANNA, PENNSYLVANIA.

LOCOMOTIVE DRIVING-BOX.

SPECIFICATION forming part of Letters Patent No. 317,774, dated May 12, 1885.

Application filed April 1, 1885. (No model.)

To all whom it may concern:

Be it known that I, WILLIAM J. HEALY, of Susquehanna, in the county of Susquehanna and State of Pennsylvania, have invented a 5 new and useful Improvement in Locomotive Driving-Boxes, of which the following is a full, clear, and exact description.

Reference is to be had to the accompanying drawings, forming a part of this specification, in which similar letters of reference indicate corresponding parts in all the views.

Figure 1 is an elevation of a locomotive driving-box to which my improvement has been applied. Fig. 2 is a cross-section of the 15 same, taken through the line *x x*, Fig. 1. Fig. 3 is a sectional plan view of the same, taken through the line *y y*, Fig. 2.

The object of this invention is to cheapen the manufacture of locomotive driving-boxes 20 and promote security and durability in the use of said boxes.

The invention consists in a locomotive driving-box, with its cellar secured in place by set-screws passing through the side of the said cellar, the heads of said set-screws resting 25 against the said box and locked in place by jam-nuts. The cellar is further secured in place by straps placed below the said cellar and secured to the bottom of the box by studs 30 and nuts. The cellar is held from lateral motion by ribs cast upon the bottom of the said cellar and resting against the straps attached to the bottom of the box. The cellar also has an opening in one of its walls which 35 is closed by an independent plate, the object of which will be hereinafter fully described.

A represents a locomotive driving-box made with grooves B on its sides to receive the wedges between which it is placed. In the 40 open bottom of the driving-box A is placed the cellar F, to receive the oil and cotton waste, to keep the driving-wheel journal lubricated. The cellar F is made so much narrower than the open bottom of the driving-box A that it can be inserted in the said open bottom in a rough state as the said box and cellar come from the molds, so that the labor and expense of planing the said parts will be avoided. In one side of the cellar F are two 45 screw-holes to receive the set-screws G, the heads of which rest against the inner surface of the driving-box A. The set-screws G are kept from working loose by jam-nuts H, placed upon them and screwed up against

the side of the cellar F. By this construction 55 the cellar F will be held firmly in place and the sides of the driving-box A (where the wedges fit) kept parallel.

On the lower corners of the driving-box A are inserted screw-studs I, passing through 60 holes in the ends of the straps J, and having nuts K screwed upon them to hold the said straps J up against the bottom of the cellar F to support the said cellar squarely in place. Upon the bottom of the cellar F are cast ribs 65 or lugs, L, in such positions as to rest against the inner edges of the straps, J, and thus hold the cellar F from lateral motion.

An opening is provided in one of the walls 70 of the cellar and closed up by an independent plate, N, secured in place by screw-stud M and nut O. The object of the plate N is to permit of removing, replacing, or oiling the cotton waste in said cellar without taking the cellar out of the driving-box.

Having thus described my invention, I 75 claim as new and desire to secure by Letters Patent—

1. In a locomotive driving-box, the combination, with the box A and the cellar F, of the 80 set-screws G and jam-nuts H, substantially as herein shown and described, whereby the said cellar will be held securely in place and the sides of the said driving-box will be supported against inward pressure, as set forth.

2. In a locomotive driving-box, the combination, with the box A, having studs I and 85 nuts K, and the cellar F, of the straps J, substantially as herein shown and described, whereby the said cellar will be supported 90 squarely in place, as set forth.

3. In a locomotive driving-box, the cellar F, made substantially as herein shown and described, with ribs L upon its bottom, to adapt the said cellar to be held from lateral 95 motion by straps attached to the bottom of the said box, as set forth.

4. In a locomotive driving box, the cellar F, provided with an opening in one wall, closed up by an independent plate, N, held in 100 its place by means of screw-stud M and nut O, allowing for the packing of the cellar without removing said cellar from its place on the locomotive, as set forth.

WILLIAM J. HEALY.
